UNITED STATES PATENT OFFICE.

SAMUEL D. GAZZOLO, OF JOLIET, ILLINOIS, ASSIGNOR OF ONE-HALF TO ANNA M. SISSON, OF JOLIET, ILLINOIS.

FOLDING PAPER BOX.

1,041,992.

Specification of Letters Patent.

Patented Oct. 22, 1912.

Application filed November 17, 1911. Serial No. 660,839.

To all whom it may concern:

Be it known that I, SAMUEL D. GAZZOLO, a citizen of the United States, residing at Joliet, in the county of Will and State of Illinois, have invented a new and useful Improvement in Folding Paper Boxes, of which the following is a specification.

My invention relates to improvements in paper-folding-boxes and the object of my 10 invention is to minimize the breakage of articles made chiefly from glass in boxing and shipping the same.

The paper box with my device is mainly intended for boxing and shipping incandescent globes, yet with variations in relative dimensions, a paper-box with my device can be used in boxing various kinds of globes.

Another object of my device is to avoid 20 the necessity of packing around a glass globe in a box, thus saving time, expense and avoiding the litter caused by packing materials, and at the same time greatly reduce the danger of breakage from concussions.

I attain these objects by the structure 25 illustrated in the accompanying drawing, in which—

Figure 1 is a perspective view of the box with ends open and all the laps and flaps 30 in view, and Fig. 2 is a view of an incandescent globe.

As appears, the whole box is made from one piece of box-paper. The flap 1 is integral with the end of a wall and hinges on 35 the same by means of scoring, and by means of further scoring forms the spacer 1' and the intermediate supporter 1'' which has the perforation 4 to receive one end of an article to be boxed. Flap 2 is a duplicate of flap 1 40 in all respects except that its perforation may have different dimensions and its members are designated as spacer 2' and supporter 2'', respectively. The closure flaps 5, 6, and 7 and tuck 7' are duplicates of 45 closure flaps 9, 10 and 8 and tuck 8', in the order named.

As my box can be used to box a great variety of articles differing in shape, size, substance and value, it will be necessary to vary the size of the box as well as the relative dimensions of its parts, the relative sizes and proportions of the spacers and perforations especially depend upon the shape of the article to be boxed. Where the article is especially valuable and end sealing is advisable, the tuck can be used as a seal, and the intermediate closure flaps may even be dispensed with. The outer flaps 7 and 8, exclusive of their tucks, and each of said supporters, each cover the cross-section 60 of the box, while said intermediate flaps, each cover only a portion of said cross-section, and for this reason, in cutting out the carton, there is paper enough to supply spacers on all sides of said supporters 1'' 65 and 2'', and I am making them with both two and four spacers each. Four spacers increase the strength for the heavier articles.

What I claim, is—

A four-sided tubular paper box, each end 70 of which is closed by four flaps, one of said flaps forming two spacing members and an intermediate supporting member, said supporting member being perforated to receive a portion of an article and of a size to fit 75 the cross-section of said box, the opposite flap forming a closure flap of a size and shape to cover the cross-section of said box and, also, carrying a tuck flap, and the intermediate flaps forming closure flaps and each 80 covering a large portion of said cross-section.

Witness my hand this 14th day of November, 1911, in the presence of two subscribing witnesses.

SAMUEL D. GAZZOLO.
